UNITED STATES PATENT OFFICE.

FRANK M. KINNARD AND ROBERT M. KINNARD, OF SEBRING, OHIO, ASSIGNEES OF ONE-HALF TO CHARLES L. SEBRING, OF SEBRING, OHIO.

SPREADER.

Application filed July 5, 1923. Serial No. 649,431.

To all whom it may concern:

Be it known that we, FRANK M. KINNARD and ROBERT M. KINNARD, both citizens of the United States, residing at Sebring, Mahoning County, Ohio, have invented a new and useful Spreader, of which the following is a specification.

This invention relates to spreaders for use in potteries for batting out clay, preparatory to placing the clay in the molds and more particularly to improvements over Letters Patent No. 1,430,309, issued September 26, 1922, to Frank M. Kinnard.

The patent referred to shows a spreader provided with a bi-bladed spreader tool, a beveled block being provided upon each blade. While this tool performs the work in a satisfactory manner, it has been found by experience that the clay creeps or crawls up the beveled faces of the block and over the rear edges of the same, making it necessary to stop the machine at frequent intervals to clean the accumulation of clay from the tool.

The objects of the present invention are to provide a spreader tool having a guard flange at the rear and side edges to prevent the clay from creeping or crawling over the same; to provide a four bladed tool upon the spreader; and to provide a spreader machine which is simple in construction and easily operated.

The above and other objects may be attained by constructing the machine as illustrated in the accompanying drawing, in which—

Figure 1 is a longitudinal section of the spreader, embodying the invention, showing the same in the operative position;

Fig. 2, a side elevation of the spreader tool;

Fig. 3, a bottom plan view of the same;

Fig. 4, a section on the line 4—4, Fig. 2, and

Fig. 5, a view similar to Fig. 4 of a slight modification of the tool.

Similar numerals of reference indicate corresponding parts throughout the drawings.

The machine is mounted upon a base 1 at the forward end of which is located the usual block 2, which receives the ball of clay. Uprights 3 are mounted upon the base near the rear end thereof and support

the channel shaped tracks 4, which may be 55 adjustable vertically upon the base, as by the adjusting screws 5.

A sliding frame 6 is mounted upon the tracks 4, being provided at its rear end with rollers 7, which extend into the channels of 60 the tracks, rollers 8 being journaled at the forward ends of the tracks in position to support the frame 6.

The sliding frame is thus connected to the track only at its rear end, thus permitting the forward end of the same to be raised by means of a handle 9, tilting the frame upward upon the rollers 7 as upon a pivot, while the rollers 8 limit the downward movement of the frame, preventing the same from being lowered beyond the horizontal.

A motor 10 is mounted upon the frame 6 and the shaft 11 thereof is provided with a beveled pinion 12 meshing with a beveled gear 13 upon the vertical spindle 14 which is journaled in the bearings 15 and 16 upon the frame.

The spreader tool indicated generally by the numeral 17, is mounted upon the lower end of the spindle 14 and comprises the hub 18 having the radially disposed blades 19, each of which has the oppositely disposed lower beveled edge 20.

As shown in Fig. 5 each blade may be 85 provided with a wooden block 21 similar to the construction shown in the prior patent referred to, the under-surface of the block having the beveled face 22 which is preferably inclined at a greater angle to 90 the horizontal than the beveled edge 20 of the blade.

To prevent creeping or crawling of the clay up this inclined surface 22, a guard plate 23, preferably of sheet metal is attached to the rear face of the block 21 and it is also preferred to provide a similar guard plate 24 at the outer end.

In the construction shown in the other figures of the drawing, the wooden block is 100 eliminated, the inclined beveled surface and the guard being formed integral from a metal plate or sheet 25 which is attached to the rear face of each blade and bent upwardly and rearwardly, as at 22^a, forming 105 the inclined surface corresponding to the under-surface of the block, the rear end of the plate being bent downward forming the

guard flange 23^a while the side end of the plate is bent down forming the guard flange 24^a.

By thus inclining the surface 22 or 22^a at 5 a greater angle than the beveled edge 20 of the blade a clearance is provided and by forming the guard plate or flange at the upper rear extremity of the inclined surface, the clay will not crawl or creep beyond said 10 guard plate, and it has been found from experience that the spreader may be operated continuously for an entire day without the necessity of stopping to clean the clay from the spreader tool, thus increasing the efficiency of the spreader considerably, and 15 making it possible for an operator to turn out a full day's work without the assistance of a helper.

The frame 6 when in the inoperative position 20 is retracted within the tracks 4, the rollers 7 upon the frame being located at the rear ends of the tracks, the stops 26 at the rear ends of the tracks limiting the rear position of the frame, the forward end of the 25 frame resting upon the rollers 8.

In order to operate the machine a ball of 30 clay is placed upon the block 2 and the handle 9 of the frame is grasped, the frame being pulled toward the operator and the forward end thereof raised sufficiently to permit the tool to clear the ball of clay.

As the frame is pulled outward the operator lowers the same to the horizontal position, the tool engaging the ball of clay and 35 spreading the same into a flat shape as indicated at 27 in Fig. 1.

The motor is operating continuously and a shield 28 may be provided to protect the operator from the spreader tool.

40 The spreader tool being rotated upon an axis at right angles to the normal plane of the block 2 forms a bat of uniform thickness and smooth surface.

After the bat, as shown at 27, is formed, 45 the frame is raised slightly at its forward end to move the tool out of engagement with the bat and the frame is pushed backward to the inoperative position to permit the operator to remove the finished bat and place another ball of clay upon the block 2.

We claim:—

1. A spreader including a slidable frame, a rotatable spreader tool carried thereby and means for rocking said frame.

2. A spreader including a horizontally 55 slidable frame, a rotatable spreader tool carried thereby and means for rocking said frame.

3. A spreader including a track, a frame 60 mounted for sliding and rocking movement upon said track and a rotatable spreader tool carried by the frame.

4. A spreader tool including a rotatable spindle, diametrically opposed blades thereon, the lower edges of the blades being oppositely beveled and members connected to the rear sides of the blades and having under surfaces inclined at a greater angle than the beveled edges of the blades.

5. A spreader tool including a rotatable 70 spindle, diametrically opposed blades thereon, the lower edges of the blades being oppositely beveled, members connected to the rear sides of the blades and having inclined under surfaces and depending guard flanges 75 at the rear edges of said members.

6. A spreader tool including a rotatable spindle, diametrically opposed blades thereon, the lower edges of the blades being oppositely beveled, members connected to the 80 rear sides of the blades and having inclined under surfaces, depending guard flanges at the rear edges of said members, and depending guard flanges at the outer ends of said members.

7. A spreader tool including a rotatable spindle, diametrically opposed blades thereon, the lower edges of the blades being oppositely beveled and members connected to the rear sides of the blades and having under surfaces inclined at a greater angle than the beveled edges of the blades, and depending guard flanges at the rear edges of said members.

8. A spreader tool including a rotatable 95 spindle, diametrically opposed blades thereon, the lower edges of the blades being oppositely beveled and members connected to the rear sides of the blades and having under surfaces inclined at a greater angle than the beveled edges of the blades and depending guard flanges at the rear edges and outer ends of said members.

In testimony that we claim the above, we have hereunto subscribed our names.

FRANK M. KINNARD,
ROBERT M. KINNARD.
